UNITED STATES PATENT OFFICE

GEORGE F. WOELFEL, OF MADISON, FLORIDA, ASSIGNOR TO THE COMMERCIAL CLEARING CORPORATION OF JACKSONVILLE, FLORIDA, A CORPORATION OF FLORIDA

COMPRESSOR FOR REFRIGERATING APPARATUS

Application filed March 1, 1928, Serial No. 258,279. Renewed July 8, 1930.

This invention relates to refrigerating apparatus and more particularly to the refrigerating systems usually employed for home or store refrigeration, wherein a compact compressor and condenser structure is employed, and wherein the compressor is usually operated directly from a motor.

In devices of this character, the operation of the compressor is fairly rapid and lubrication thereof is considerable of a problem. The lubricant employed will often vaporize and pass from the compressor to the refrigerating system where it is condensed by the refrigerant and collects in the refrigerant chamber often to such an extent that it will prevent the refrigerant from performing its function. Such an action in addition to interfering with proper refrigeration, rapidly removes the lubricant necessary to the proper operation of the compressor, with the result that the compressor sticks or is rendered inoperative by burned bearings or the like. Accordingly, an important object of the invention is the provision of a structure such that oil which is vaporized and withdrawn from the compressor in this fashion may be conveniently returned thereto, so that breakdowns from this cause are prevented.

A further object of the invention is to provide a structure of this character permitting the use of a greater quantity of lubricant than is necessary to the proper lubrication of the compressor and providing means for controlling the amount actually present in the compressor to maintain the same at a proper point.

A further object of the invention is to provide a novel compressor construction enabling the production of a system of this character.

A further and more specific object of the invention is to provide a novel and improved valve structure for such compressors enabling the vaporized lubricant to be withdrawn and conducted to the refrigerant chamber, so that it may be condensed and prepared for reuse.

A still further object of the invention is to provide a novel and improved means for maintaining a valve controlling the com-

pressor in proper engagement with its seat during all times when the compressor is in operation, and which is of such character that when operation of the compressor is checked, pressure upon the valve is relieved, so that the starting load imposed by the compressor is materially reduced.

A further object of the invention is the provision in a construction of this character of a valve seating element, maintaining the valve in engagement with its seat, of such character that adjustment to compensate for wear is unnecessary.

A further object of the invention is the provision of a structure such that the valve operating mechanism may be entirely enclosed within the compressor, thus eliminating the necessity for stuffing boxes and other equipment which would otherwise be necessary.

A further object of the invention is to provide a novel and improved air cooled condensing apparatus which may be constructed in capacities running as high as several tons, thereby making it available for use on moving cars, trucks or other vehicles where the power for its operation may be provided from some moving part of the vehicle, and wherein the structure is such that the starting load of the vehicle is not increased by the addition of the refrigerating apparatus.

These and other objects I attain by the construction shown in the accompanying drawings, wherein for the purpose of illustration is shown a preferred embodiment of my invention and wherein:

Figure 1 is a side elevation partially in section showing refrigerating apparatus constructed in accordance with my invention;

Figure 2 is an enlarged sectional view through the compressor;

Figure 3 is a section on the line 3-3 of Figure 2;

Figure 4 is a section on the line 4-4 of Figure 2;

Figure 5 is a detail sectional view through the oil level control.

Referring now more particularly to the drawings, the numeral 10 generally desig-

nates a base having mounted thereon a compressor 11, a condenser 12 and a motor 13. The motor shaft 14 operates both the movable elements of the compressor and a cooling fan 15 for directing cooling air upon both the condenser and the compressor. To this end, the condenser 12 is arranged upon the base between the compressor and motor and the fan secured to the motor shaft 14 between the motor and the condenser, so that air passes through the condenser, which is at present disclosed as of the honey-comb type, for engagement against the compressor.

The compressor includes a cylinder 16, a crank case 17 and a suction chamber 18. The walls 19 separating the cylinder and suction chamber is formed with a flat face 20 at the suction chamber against which operates a slide valve 21 having a port 22 extending therethrough and a second port 23, one end of which is in continuous communication with the interior of the suction chamber. The interior of this suction chamber is in continuous communication with the crank case 17. The crank shaft 24, which is directly connected with the motor shaft and forms a continuation thereof, mounts a connecting rod 25 for the piston 26 of the cylinders 16, and further mounts a shank or rod of the slide valve 21, as indicated at 27, and is integrally formed with the valve.

The outer wall of the suction chamber 18 is formed by a removable plate 28 having an opening 29 formed therein. Extending inwardly from opposite sides of the opening are guides 30 between the inner ends of which the valve 21 operates. The upper and lower faces of these guides outwardly of the plates are connected by horizontal guides 31 combining with the guides 30 to provide a rectangular guide opening within which a metallic block 32 is mounted to slide toward and away from the valve. This block is chambered at 33 and has a port 34 at its inner face with which the outer end of the port 22 of the valve 21 aligns at the same time that the inner end of this port aligns with a port 341 extending through the wall 19 and opening into the cylinder 16. The outer end of the chamber 33 communicates with the interior of a bellows-like metal structure 35 which is sealed to the block 32 at its inner end and at its outer end is sealed to a plate 36 closing the opening 29.

This plate has connected thereto a discharge line 37 communicating with the intake of the condenser 12. The numeral 38 generally designates a refrigerant chamber, with the upper end of which are connected an intake conduit 39 which communicates with the suction chamber of the compressor and a conduit 40 communicating with the discharge of the condenser. The lower end of the refrigerant chamber at the low side thereof has connected thereto a conduit 41,

the lower end of which communicates with a chamber 42 having arranged therein a float valve 43 controlling communication between the conduit and the chamber. The chamber 42 communicates with the crank case 17 and the float valve 43 closes communication with the conduit at the time when the oil level within the crank case is correct.

In the use of a system of this character, it will be understood that the refrigerant employed and indicated at 44 should be of less specific gravity than the oil, indicated at 45, so that this oil, when condensed and delivered to the refrigerant chamber 38, will settle therein. This oil may then pass directly through the conduit 41 to return to the base in such quantities as it is needed. It will be obvious that any oil evaporated in the course of operation of the machine will become intermingled with the gas drawn into the suction chamber and in common with this gas, will pass through the port 23 into the cylinder 16 when this port is aligned with the port 34. When the port 22 of the valve aligns with the port 34 and the piston 26 is rising, this gas will be compressed and passed through the ports 22 and 34 to the chamber 33 and from thence through the bellows-like structure 35 and conduit 37 to the condenser. The pressure generated within the bellows-like structure will cause the same to expand, forcing the block 32 against the valve 21 and the valve 21 against its seat, so that a perfect seal is provided. When, however, operation of the machine is checked for any reason and the pressures equalized, this block will be withdrawn so that the valve 13 is relieved in its frictional engagement with its seat and starting of the compressor may be much more readily accomplished. This enables efficient use of a less expensive motor than would otherwise be necessary, while at the same time, insuring a proper seal at all times during operation.

Such a system as above described eliminates the necessity for the use of oil traps and receivers and for constant attendance of a compressor to insure proper lubrication thereof. In this connection, it is pointed out that excess oil may be present in the refrigerant chamber in any quantity which will not interfere with proper functioning of the refrigerant and that this excess oil will be delivered to the base of the compressor as it becomes necessary.

While I have above referred to the use of a motor and have illustrated the use of an electrical motor, it will, of course, be understood that the term "motor" as employed is intended to cover the use of other power apparatus than the specific form illustrated. For example, the apparatus might receive its power from a moving part of a vehicle upon which it is mounted, as hereinbefore set forth. Where this is the case, the load im-

posed upon the vehicle in starting is not noticeably increased as the resistance of the apparatus to operation does not take place until pressure has been built up in the system 5 sufficient to cause a complete seating of the valve. Attention is also directed to the fact that this valve, due to the seating mechanism employed therewith, is wear-compensating and any adjustment or repairs thereto is 10 eliminated for a very considerable period, thereby admirably adapting the same for use in the situations just described.

Since the construction employed is obviously capable of a certain range of change 15 and modification without materially departing from the spirit of the invention, I do not limit myself to such specific structure except as hereinafter claimed.

I claim:—

20 1. In a refrigerating system, a compressor including, in combination, a compressor cylinder, a piston reciprocating therein, a crank shaft for the piston, a motor operating the crank shaft, a valve controlling the intake 25 and exhaust of gases from the cylinders, means conducting the exhaust of the cylinder from the compressor including a part operating under the pressure of the exhaust to apply pressure to the valve to maintain the 30 same in engagement with its seat.

2. In a refrigerating system, a compressor including, in combination, a compressor cylinder, a piston reciprocating therein, an intake chamber having a port connecting the 35 intake chamber and cylinder, an exhaust conduit, a single slide valve alternately placing said port in communication with the exhaust conduit and the intake chamber, and means in the exhaust conduit expanding under pressure of the exhaust to apply pressure maintaining the slide valve against its seat.

3. In a refrigerating system, a compressor including, in combination, a compressor cylinder, a piston reciprocating therein, an intake chamber having a port connecting the intake chamber and cylinder, an exhaust conduit, a single slide valve alternately placing said port in communication with the exhaust conduit and the intake chamber, the 50 exhaust conduit including an expandable section responding to pressure of the exhaust and when responsive thereto applying pressure to maintain the valve in engagement with its seat.

55 4. In a refrigerating system, a compressor including, in combination, a compressor cylinder, a piston reciprocating therein, an intake chamber having a port connecting the 60 intake chamber and cylinder, an exhaust conduit, a single slide valve alternately placing said port in communication with the exhaust conduit and the intake chamber, the exhaust conduit including a flexible bellows-like section disposed in the intake chamber and fixed

at one end and at its opposite end operatively engaging said valve.

5. In a refrigerating system, a compressor including, in combination, a compressor cylinder, a piston reciprocating therein, an intake chamber having a port through one wall of the intake chamber connecting the intake chamber and cylinder, a single slide valve coacting with said port and operating against said wall, the opposite wall of the intake 75 chamber being removable, an exhaust conduit extending therethrough, said exhaust chamber within the intake chamber including a flexible section resiliently maintaining the slide valve in engagement with its seat. 70 80

6. In a refrigerating system, a compressor including, in combination, a compressor cylinder, a piston reciprocating therein, an intake chamber having a port through one wall of the intake chamber connecting the intake 85 chamber and cylinder, a single slide valve coacting with said port and operating against said wall, the opposite wall of the intake chamber being removable, an exhaust conduit extending therethrough, said exhaust chamber within the intake chamber including a flexible section resiliently maintaining the slide valve in engagement with its seat, said section expanding under pressure of the exhaust to increase its application of pressure 90 to the slide valve. 95

7. In a refrigerating system, a compressor including, in combination, a compressor cylinder, a piston reciprocating therein, an intake chamber having a port through one wall of the intake chamber connecting the intake chamber and cylinder, a single slide valve coacting with said port and operating against said wall, the opposite wall of the intake chamber being removable, an exhaust conduit extending therethrough, said exhaust chamber within the intake chamber including a flexible section resiliently maintaining the slide valve in engagement with its seat, 100 said section being of bellows-like structure 105 and expanding under the influence of the exhaust to increase the pressure applied to the slide valve. 110

In testimony whereof I hereunto affix my 115 signature.

GEORGE F. WOELFEL.
